(57) **CLAIM**

I claim the ornamental design for a powered planer, substantially as shown.

DESCRIPTION

FIG. 1 is a perspective view of the powered planer.

FIG. 2 is a side view of the powered planer.

FIG. 3 is a rear view of the powered planer.

FIG. 4 is a front view of the powered planer.

FIG. 5 is a top view of the powered planer.

FIG. 6 is a bottom view of the powered planer; and,

FIG. 7 is an opposite side view of the powered planer.

The broken lines shown in the drawings form no part of the claimed design.
